CARBURETOR STEP-UP CONTROL

Leonard D. Boyce, Maplewood, Mo., assignor to
 Carter Carburetor Corporation, St. Louis, Mo.,
 a corporation of Delaware

Application February 7, 1939, Serial No. 255,154

2 Claims. (Cl. 261—69)

This invention relates to carburetors for internal combustion engines and particularly to so-called step-up mechanisms therefor.

Most automotive carburetors now in use are provided with means for enriching the mixture supplied when the associated engine is subjected to an extra heavy load. Such means may take the form of a device responsive to suction posterior to the throttle for opening an auxiliary metering jet or for enlarging the effective area of the main metering jet, or the device may be operated mechanically from the throttle valve. The step-up device is ordinarily necessary only under extreme load conditions, and during most driving, an automobile engine will function to the satisfaction of the driver without this auxiliary fuel. Obviously, operation of the step-up device affects the economical operation of the vehicle.

Accordingly, it is an object of this invention to provide thermostatic means for restricting or preventing the operation of the step-up device under relatively high temperature conditions.

This object and other more detailed objects hereafter appearing are attained substantially by the device illustrated in the accompanying drawing, in which:

Fig. 1 is a vertical transverse section illustrating a carburetor embodying the invention.

Fig. 2 is a view of a portion of the structure shown in Fig. 1, but with parts in different operative positions.

The carburetor shown includes an air horn 1, venturi 2, and outlet portion 3 forming a mixture conduit, the outlet portion being flanged as at 4 for attachment to the intake manifold (not shown) of an associated internal combustion engine. A choke valve 5 is mounted in the air horn and a throttle valve 6 is located near the outlet portion. Adjacent the mixture conduit is a bowl 7 within which fuel is maintained at a substantially constant level by the usual needle valve mechanism 8 controlled by a float 9. Fuel for normal operation is supplied to the mixture conduit through a calibrated metering orifice member 10 and main nozzle 11 terminating at the throat of the upper venturi 2.

There is also provided a suction step-up device including an additional orifice member 12 opening into the main nozzle passage and controlled by a needle 13 extending through a guide 14 and yieldingly secured at its upper end through coiled spring 15 to a strap 16. Adjacent needle 13 is a cylinder 17 communicating through passage 18 with the carburetor mixture conduit posterior to

throttle 6. A piston 19 is slidable in cylinder 17 and constantly urged upwardly by coiled spring 20. Strap 16 is secured to piston 19 whereby needle 13 reciprocates vertically with the piston responsive to suction conditions in the mixture conduit. The various parts are constructed so that when the engine intake suction drops below a predetermined value, on the order of two inches of mercury, spring 20 will force piston 19 and needle 13 upwardly, opening auxiliary orifice member 12 to supply additional fuel to the mixture conduit.

A reach pin 21 is slidable in an apertured boss or bearing 22, carried in a recessed portion 23 of the float bowl cover and, at its upper end, is connected by a link 24 to one arm of a bell crank 25, pivotally mounted at 26 on a bracket 27 projecting above the bowl cover. A Bowden wire 28 is secured to the other arm of bell crank 25 and preferably extends to the dash-board of the vehicle or another point convenient to the operator from the driver's seat. This mechanism is arranged so that when Bowden wire 28 is pushed inwardly, reach pin 21 is moved downwardly against suction piston 19 so as to limit or prevent upward movement thereof under the influence of spring 20 and, consequently, limit or prevent opening of the step-up orifice. Thus the step-up device may be manually controlled at the option of the driver. When wire 28 is pulled outwardly, or to the left, sufficient space is provided between pin 21 and piston 19, as shown in Fig. 2, to permit normal operation of the step-up.

The invention is intended for use with any sort of step-up device having a member yieldably movable with the step-up needle or valve. The form of the manual control and also various features of the carburetor are not essential and these may be modified as will occur to those skilled in the art. The exclusive use of all modifications as come within the scope of the appended claims is contemplated.

I claim:

1. In combination with an internal combustion engine intake conduit, a carburetor for association with said intake conduit including a manually actuated throttle, a float bowl and a cover therefor, a main fuel passage for admitting fuel from said bowl to said conduit during normal operation of the engine, an auxiliary fuel passage opening into the main fuel passage for enriching the mixture in said conduit, a valve associated with said auxiliary fuel supply passage, suction responsive means including a piston for normally actuating said valve in response to

- suction variations in said conduit to automatically enrich the mixture in said conduit when the pressure in the intake passage decreases to a predetermined value, a guide member supported by the cover of the float bowl, a slideable element in said guideway for engagement with said piston, and manually actuated means supported by the carburetor for causing the slideable member to engage said piston to cause the latter to positively move said valve to closed position whereby the normal suction actuation of said valve is prevented and the fuel supply to said conduit is limited to the main fuel passage.
2. In combination with an internal combustion engine intake conduit, a carburetor for association with said intake conduit including a manually actuated throttle, a float bowl and a cover therefor, a main fuel passage for admitting fuel from said bowl to said conduit during normal operation of the engine, an auxiliary fuel passage opening into the main fuel passage for enriching

the mixture in said conduit, a valve associated with said auxiliary fuel supply passage, suction responsive means including a piston for normally actuating said valve in response to suction variations in said conduit to automatically enrich the mixture in said conduit when the pressure in the intake passage decreases to a predetermined value, a guide opening formed in the cover of said float bowl in alignment with said piston, a reach pin movable in said guide opening for engagement with said piston, a bracket mounted on said structure, a bell crank pivoted to said bracket having one arm operably connected with said pin, and manual means for moving said bell crank on its pivot to cause said reach pin to move said valve to closed position, whereby the movement of said fuel supply to said conduit is limited to the capacity of the main fuel passage and normal suction actuation of said valve is prevented.

LEONARD D. BOYCE.
